Ontario, Canada

Filed Apr. 1, 1965, Ser. No. 84,554

Term of patent 3½ years

(Cl. D14—14)

FIG. 1

FIG. 2

FIG. 3

FIG. 1 is a bottom perspective view, taken from the rear and from one side, of a baby walker embodying my new design;

FIG. 2 is a perspective view from above of the baby walker of FIG. 1, taken from the front and from the other side; and

FIG. 3 is a side elevation of the baby walker of FIGS. 1 and 2.

The dominant features of my design reside in those portions shown in full lines on the drawing.

I claim:

The ornamental design for a baby walker, as shown and described.
